UNITED STATES PATENT OFFICE.

FREDERICK RIEHL, OF ALAMEDA, CALIFORNIA.

DIRIGIBLE KITE.

No. 892,009.

Specification of Letters Patent.

Patented June 30, 1908.

Application filed September 17, 1907. Serial No. 393,389.

To all whom it may concern:

Be it known that I, FREDERICK RIEHL, a citizen of the United States, and a resident of Alameda, in the county of Alameda and 5 State of California, have invented new and useful Improvements in Dirigible Kites, of which the following is a specification.

This invention has for its object to provide a kite for life-saving purposes, and which is 10 especially adapted by its construction to carry a line from a vessel to the shore, or to support and carry a person from a wreck to the shore through breakers, or a heavy surf, with safety.

15 The novel features of the invention comprise a construction of separable frame and a removable covering or body, capable of being folded or brought to a compact form to occupy little room, and of being quickly set up 20 for use by a person of ordinary intelligence, the parts of the structure being adapted to retain their several positions when in use and even when exposed to high winds; and of having great lifting power in proportion to 25 the size and dimensions of the frame and the covering.

The invention comprises, further, a novel means of controlling or giving direction to the kite in its flight with reference to the direction of the wind, whereby it can be caused 30 to take a direction at varying angles to the wind, and to be directed in its flight towards different points of the compass within a limited arc either to the right or to the left of the 35 point to which the wind may be blowing.

The construction of my improved dirigible kite and the manner in which the same is used and operated, is explained at length in the following description, in which the accompanying drawings forming a part of this 40 specification are referred to by figures and letters.

Figure 1 of the drawing represents in elevation a dirigible kite of my invention, the same being a view from behind. Fig. 2 is a side view of Fig. 1. Fig. 3 is a detail, on an enlarged scale, of a portion of the frame and covering at one end of the cross-arm. Fig. 4 is a transverse section, showing in detail the 45 construction of the back-bone or perpendicular member of the frame. Fig. 5 illustrates the kite taken apart and folded for carrying or stowing away. Fig. 6 is a diagram, illustrative of the dirigible feature of the kite. Fig. 7 illustrates the manner of operating the 50 kite to carry a person from a vessel to the 55 shore in case of a shipwreck. Fig. 8 is an elevation of a portion of the kite frame showing the connection between the back-bone and the horizontal member, the latter being 60 shown in section.

The required qualities of lightness and strength in the structure of a kite for the purposes of my invention are secured in a high degree by the construction of the two members of the frame, each of which is composed of a relatively thin and narrow bar or slat 2 of wood, and a rib 3 of about the same dimensions in breadth and thickness as the bar 2, but of less length. These two parts are 70 secured together by cords 4 whipped or wound tightly around the bar and the rib in a number of turns at both ends of the rib, and at intervals apart in its length. This construction is peculiar in the feature of dispensing 75 with nails, screws, pins or other metal fastenings of any character, the result of which is that the strength of the bar or the rib is not weakened at any point, as they would be if metal fastenings were inserted or 80 fixed in them; and the weight of the parts is kept within the limits of extreme lightness 85 by dispensing with such fastenings.

The cross-arm B rests on and is supported by a block 5 lashed on the front side of the 85 back-bone A, and it is kept in place on the block by the cord D that forms the belly-band of the kite, the latter being secured to the back-bone for that purpose at a point 7, so that it lies under the cross-arm. The effect 90 of this arrangement is to keep the cross-arm always in position on the block, without requiring an additional fastening means. This arrangement is illustrated in detail in Fig. 8, wherein it will be seen that the cross-arm will be held against the back-bone by the pressure of the wind against the covering, and will be prevented from slipping off the 95 block and dropping out of place by the belly-band when the latter is under strain. Notches 9 are provided in the ends of the back-bone and the cross-arm, to receive the 100 marginal cord 10 by means of which the covering C is stretched upon and secured to the frame. At each corner, or angle, the covering is provided with a cap 12 attached to the fabric, but detached from the cord 10, so that the cord may readily be set in the notch or be 105 unslipped from it when removing the cover, and when the cap is drawn over the end of the stick it will prevent the cord from slipping 110 out of place.

A novel feature in the dirigible kite of my invention consists in providing reefing-cords E E on the covering, or a means whereby the slackness or looseness of the body C of the kite can be taken up at will on either side of the back-bone or longitudinal central member of the kite, for the purpose of varying the extent or degree of the "bellying" quality of the kite-body on one side in excess of that on the opposite side of the longitudinal median line. The effect of producing such variation is to cause the kite to veer or change the direction of its flight before the wind, to a greater or less angle or degree laterally to wards that side of the point dead ahead which coincides with that side of the kite which is reefed or taken in; and thus place the dirigibility of the kite with reference to different points of the compass to one side or the other of the direction in which the kite would generally fly, if not so controlled. This operation will readily be understood from the diagram Fig. 6, in which the arrows indicate the direction of the wind. With the reefing-cords E loose, the kite A will fly directly before the wind in the ordinary manner. But with the cords E—E on the right side of the kite tied, it will fly towards the right and assume a position at an angle to the direction of the wind as indicated at A². On the other hand, if the reefing-cords E¹—E¹ on the opposite side be tied to the back-bone so as to draw the covering taut on that side of the center, the kite will fly to the left in the direction indicated at A¹; the angular variation being greater or less in either case, according to the degree of slackness or tautness

produced in the covering by means of the reefing-cords. These cords are used to secure that end by passing one cord of the pair around the back-bone, and then drawing on both cords of the pair and tying them together.

Having thus described my invention, what I claim is:—

1. A kite comprising a frame composed of a longitudinal back-bone and a cross-arm, each composed of a flat-bar and a rib set side-wise on the bar and fastened thereto by lashing-cords; a block on the front of the back-bone adapted to form a support for the cross-arm; a flexible covering secured to the frame at the ends of the back-bone and the cross-arm, and a belly-band secured to the back-bone on a line with the top face of the block supporting the cross-arm, so as to lie under said cross-arm.

2. A kite comprising a frame having a longitudinal back-bone and a flexible covering forming the body, and reefing-cords on said body situated on opposite sides of the back-bone of the frame as a means of varying the looseness or slack of the covering on one side of the line of said back-bone over that on the opposite side.

3. The herein described dirigible kite, comprising a frame a flexible covering therefor, and means on both sides of the longitudinal median line of the kite for reefing the covering.

FREDERICK RIEHL.
